Since wire resistances of wires among the four gate driving sub-circuits on the left side of the display panel 60 may exist, and wire resistances of wires among the four gate driving sub-circuits on the right side of

The specific example of the display device according to the present disclosure adopts an output control signal outputted by TCON as a selection signal for the amplitude control main circuit, values of the gate-driving-power voltages are controlled by using the transistors and programmable resistor and thereby compensating differences among the gate driving on-voltages received by the gate driving sub-circuits, so that amplitudes of the gate driving voltages outputted by the gate driving sub-circuits according to the gate driving on-voltages received by the gate driving circuits are approximately the same, thereby eliminating the phenomenon that the image displayed in the display panel is split into four parts.

An operational flow of the specific example of the display device according to the present disclosure is as follows. gate-driving scan operations of the G-COF11, the G-COF12, the G-COF13, the G-COF14 are performed sequentially, and gate-driving scan operations of the G-COF21, the G-COF22, the G-COF23, the G-COF24 are performed sequentially, i.e., the display panel performs the gate-driving scan operations from the distal end to the proximal end when displaying an image.

As shown in FIG. 8, at a beginning of a duration for displaying a frame, i.e. at a blank time period tb0 and at a first scan time period t1 of the first gate driving sub-circuits, the output control terminal CS outputs a low electrical level, an electrical potential of the switch control node Po is changed to a high electrical level, and an electrical potential of the phase inversion node SF is changed to the low electrical level under an action of the phase inverter D1, the first switch transistor M1 is turned on, and the second switch transistor M2 is turned off, so that the VGH-OUT outputs the reference power voltage VGH0.

After a last gate line driven by the first gate driving sub-circuits is scanned, and at a second scan time period t2 of the second gate driving sub-circuits, the output control terminal CS outputs the high electrical level, the electrical potential of the switch control node Po is changed to the low electrical level, and the electrical potential of the phase inversion node SF is changed to the high electrical level under the action of the phase inverter D1, the first switch transistor M1 is turned off, the second switch transistor M2 is turned on, and a resistance value of the programmable resistor RP is changed to 'r' under a control of the resistance control terminal RS, wherein the r is a predetermined resistance value, and the gate-driving-power-voltage output terminal VGH-OUT outputs the first power voltage VGH1.

After a last gate line driven by the second gate driving sub-circuits is scanned, and at a third scan time period t3 of the third gate driving sub-circuits, the output control terminal CS outputs the high electrical level, the electrical potential of the switch control node Po is still the low electrical level, and the electrical potential of the phase inversion node SF is changed to the high electrical level under the action of the phase inverter D1, the first switch transistor M1 is turned off, the second switch transistor M2 is turned on, and the resistance value of the programmable resistor RP is changed to '2r' under a control of the resistance control terminal RS,

and the gate-driving-power-voltage output terminal VGH-OUT outputs a second gate driving power voltage VGH2.

After a last gate line driven by the third gate driving sub-circuits is scanned, and at a fourth scan time period t4 of the fourth gate driving sub-circuits, the output control terminal CS outputs the high electrical level, the electrical potential of the switch control node Po is still the low electrical level, and the electrical potential of the phase inversion node SF is changed to the high electrical level under the action of the phase inverter D1, the first switch transistor M1 is turned off, the second switch transistor M2 is turned on, and the resistance value of the programmable resistor RP is changed to '3r' under a control of the resistance control terminal RS, and the gate-driving-power-voltage output terminal VGH-OUT outputs a third gate driving power voltage VGH3.

After a last gate line driven by the fourth gate driving sub-circuits is scanned, a next blank time period tb1 starts, the output control terminal CS outputs the low electrical level again, and the gate-driving-power-voltage output terminal VGH-OUT outputs the reference power voltage VGH0.

When the specific example of the display device according to the present disclosure operates, the reference power voltage VGH0 is larger than the first power voltage VGH1, the first power voltage VGH1 is larger than the second power voltage VGH2, the second power voltage VGH2 is larger than the third power voltage VGH3, and voltage differences among the gate driving sub-circuits are compensated by setting a value of the 'r'. In actual applications, the 'r' may be a wire resistance between two adjacent ones of the gate driving sub-circuits.

In FIG. 8, the output enable terminal OE1 outputs an enable signal, CPV is a Clock Pulse Vertical signal, STV is a start signal. When the electrical potential of the output enable terminal OE1 is the high electrical level, the electrical potential of the gate driving on-voltage VON is the low electrical level (i.e., the off voltage); and, when the electrical potential of the output enable terminal OE1 is the low electrical level, the electrical potential of the gate driving on-voltage VON equals to the gate-driving power voltage.

In the specific example of the display device according to the present disclosure, selection of the gate driving power voltages outputted by the gate-driving-on-voltage output terminal VGH-OUT is controlled by the TCON, a response time is short, and values of the gate driving power voltages are adjusted by software.
